APPARATUS FOR GRINDING CURVED BLADES

Harlin W. Barnard, Olean, N. Y.

Application January 29, 1938, Serial No. 187,739

3 Claims. (Cl. 51—100)

This invention relates to means for grinding cutting blades and its principal object is to provide means of uniformly beveling the surface of the blade terminating in the cutting edge, of blades having compound edge curvature, that is to say, blades having different portions of their edges curved on different centers of curvature.

The primary object of this invention is to provide means for grinding a knife blade with a bevel edge wherein the line of bevel will be substantially concentric with the varying curvature of the cutting edge by the use of a specially designed blade holder adapted to be moved in fixed relation to the grinding means and bringing all points of the edge of a compound curved blade progressively into bevel forming positions, in relation to the grinding means whereby a blade having an edge formed in two or more curves, a curve of short radius near the blade point, merging into a curve, or curves of long radii in the body of the blade, will be provided with a uniform bevel throughout its cutting edge.

The apparatus herein shown comprises as its principal units, a blade holder with a controlling factor for accurately determining the path and position of the blade holder at various points in its movement with relation to the grinding and sharpening means.

These and other features of the invention will be more clearly understood from the following description thereof, together with the accompanying drawing, in which—

Fig. 1 is a view in side elevation of the blade holder assembled with a knife blade positioned therein.

Fig. 2 is a plan view of the outline of a blade blank adapted to be positioned in the blade holder.

Fig. 3 is a plan view of one of the pair of side plates forming the blade holder.

Fig. 4 is a plan view of the bottom element of the blade holder adapted to be positioned intermediate of the side plates in the blade holder assembly.

Fig. 5 shows a cross section view of the blade holder and blade shown in Fig. 1 on the line 5—5.

Fig. 6 shows a cross section view of the blade holder and blade on the line 6—6.

Fig. 7 is a view in side elevation of the blade holder with a blade positioned therein preparatory to the grinding operation.

Fig. 8 is an end view of the companion grinding disk with the blade holder with blade therein positioned for the grinding operation.

In the drawing Figs. 1 to 4 inclusive, are shown the component parts of the blade holder assem-

bly 5, wherein 10 designates the bottom part of the blade holder, 11 designates one of the companion side plates adapted to be riveted together with the bottom element 10 interposed therebetween to form a trough into which the blade is 5 positioned.

The bottom element 10 has a definitely shaped outline on both edges, the object of which will be more fully explained.

As shown in Fig. 2 the knife blade blank 12 10 is formed with a contour at its back edge providing shoulders formed at 1 and 2. This contour conforms to the shape of the blade contacting edge of the bottom element 10 shown in Fig. 4. As the back of the blade blank 12 rests upon 15 the bottom element 10, the shoulders 1 and 2 will maintain the blade blank 12 against lateral movement within the blade holder 5 by the shoulders 1 and 2 registering in the depressions 3 and 4 of the bottom element 10. 20

Further resistance to lateral movement of the blade 12 is provided by the extension 13 of the member 10 which engages the end of the tang portion of the blade 12. 25

To afford suitable grinding means there is provided, as shown in Fig. 8, a pair of companion grinding disks 15 and 15' formed of any suitable abrasive medium, mounted upon suitable arbors, rotatively mounted in bearings well known in the art (not shown) the arbor of the one companion 30 disk 15' being held in a fixed position, and the arbor of the other companion disk 15, being adapted to move in a horizontal plane toward and away from the companion disk 15' mounted on the fixed positioned arbor, by means well known 35 in the art (not shown).

Positioned in a vertical plane on a line between the peripheries of the companion disks 15 and 15' is an adjustable standard or post 14, upon which the back of the knife blade holder 10 is 40 adapted to contact in its movement during the grinding operation.

The form of the blade holder element 10 forms an important part of this invention, as will be appreciated as the grinding operation is more 45 fully described as follows:

With the blade blank 12, positioned in the blade holder 5, as shown in Fig. 1 the blade holder with the blade therein is placed in position between the grinding disks 15 and 15' with 50 the back member 10 of the blade holder resting upon the support 14 as shown in Figs. 7 and 8.

With the edge of the blade blank 12 interposed between the companion disks 15 and 15' in a grinding contact therewith, the blade holder 55

5, is moved horizontally with the blade holder element 10 resting upon the supporting element 14, which so guides the top edge of the blade blank 12, with respect to its relation with the 10 grinding disks that the line of bevel shown as 15 in Fig. 1 will be substantially parallel with the outline of the bottom edge of element 10 contacting the top of the supporting element 14.

It will be obvious that other forms of curved 10 surface elements 10 may be provided to form other contours of the line of bevel as well as the contour of the cutting edge of blades of other shapes.

In the movement of the blade holder 5 as 15 shown in Fig. 7 from right to left, as the element 10 moves on top of the supporting element 14, the declining curve formed in the terminal of the element 10 will cause the blade holder 5 to change its path of movement to apply the 20 cutting edge of the knife blade to the abrasive means along a line of curvature determined by the arc of the curve formed in the terminal of the element 10. It will be obvious from the 25 foregoing description of its operation, that with my improved apparatus, knife blades having curved cutting edges may be readily ground by inexperienced operators to produce a line of bevel extending back from the cutting edge, a predetermined distance and concentric with the 30 cutting edge.

It will be obvious to those skilled in the art, that a uniform bevel will be formed on both sides of the blade in the one operation.

Having thus described my invention, what I 35 claim as new and desire to secure by Letters Patent is:

1. In a grinder for knives having compound

curved cutting edges, the combination with a pair of grinding wheels, a support intermediate thereof, a portable blade holder associated with said support and adapted for lateral movement thereon with its support contacting surface formed in a compound curve whereby successive portions of the curved cutting edge of the knife may be selectively applied to the grinding wheels during a lateral movement of the blade holder.

2. In a grinding device for knives having compound curved cutting edges, the combination with a frame of a pair of grinding wheels mounted for adjustable relation therein, a support intermediate of said wheels, a portable blade holder associated with said support and adapted for lateral movement thereon having its support contacting surface formed in a compound curve whereby in its lateral movement, successive portions of the compound curved cutting edge of the knife may be selectively applied to the grinding wheels.

3. In a grinder for knives having compound cutting edges, the combination with a frame of a pair of grinding wheels mounted in said frame to be moved in adjustable relation to each other, and adjustable support intermediate of said wheels, a portable knife blade holder associated with said support and adapted for lateral movement thereon formed with its contacting surface in a compound curve whereby in its lateral movement, successive portions of the compound curved cutting edge of the knife may be selectively applied to both grinding wheels during the lateral movement of the blade holder.

HARLIN W. BARNARD.
